AUTOMATIC DIAL SCALE

Alfred Bousfield, St. Johnsbury, Vt., assignor to
 E. and T. Fairbanks and Company, St. Johnsbury, Vt., a corporation of Vermont

Application May 14, 1932, Serial No. 611,284

15 Claims. (Cl. 265—62)

This invention relates to improvements in automatic dial scales, particularly to scales of that type employing suspended sectors co-operating with load offsetting pendulums.

It has been found in previous mechanisms of a similar general class developed in the art that there has been insufficient power delivered by the actuating mechanism to the rack operating the indicator pinion to properly overcome the friction present in the bearings of the indicator, thereby causing inefficient operation of the indicator and resultant inaccuracies of weight indications. The present invention is designed to overcome these difficulties and to provide simple and efficient mechanism to accomplish the desired results.

It is, therefore, an outstanding object of the invention to provide means for delivering a powerful driving force to the indicator pinion and hence to the indicator and thereby assist in increasing the accuracy and the sensibility of the indicator by reason of the greater power provided to overcome the friction in the indicator bearings and the indicator driving mechanism.

Another object is to provide an improved dial head mechanism consisting primarily of opposed groups of co-acting sectors comprising load cam sectors, fulcrum sectors, driving sectors and pendulum sectors and constituting a balanced mechanism controlled and operated by a load cross bar under influence of the load, the fulcrum sectors being flexibly suspended from the dial head housing by steel tapes, while the load cam sectors, driving sectors and pendulum sectors are flexibly connected by steel tapes to their co-operating mechanism including a centrally and vertically disposed indicator driving bracket, whereby the force transmitted by the load causes the fulcrum sectors to be rolled up on their steel tapes and thus are established fulcrum points which are automatically variable in accordance with the variation of the load.

Another object is to provide means for exerting a powerful direct line pull upon the sector driving mechanism, initiated by the load and transmitted continuously in a direct line without any deflection, through an improved linkage system leading directly from the scale levers to a load cross bar operating the sector driving and indicator driving mechanisms, whereby a powerful pull is caused to be exerted by the driving bracket actuating the indicator.

Another object is to provide an improved indicator driving bracket, which is designed to operate entirely in a vertical plane and to be

operatively connected on each side to the tape secured to the respective driving sector and its co-operating pendulum sector, whereby the pull upon the driving bracket and its co-operating rack engaging the indicator pinion is exerted in a vertical direction constantly. 5

Another object is to provide means for transmitting the load from the load cam sectors to the driving sectors together with adjusting means for effecting ready adjustment of the various 10 steel tapes of the sectors as well as the steel tapes of the fulcrum sectors with resulting adjustment of the load cam sectors in properly sealing the dial head mechanism.

In order that the nature of my invention may 15 be fully understood, I have illustrated certain embodiments of the invention in the accompanying drawings, in which,—

Figure 1 is a front elevation, of the dial head mechanism, with the dial glass frame and dial 20 plate removed, showing the mounting of the dial head mechanism in its housing and its co-operative relation to the scale beam and embodying a preferred form of my invention.

Figure 2 is an enlarged rear elevation of the 25 dial head mechanism with a portion of the assembly bracket removed in order to show certain parts of the interior of the dial head mechanism.

Figure 3 is a central cross section on the line 30 3—3 of Fig. 1, showing the assembly bracket and co-operating parts.

Figure 4 is a fragmentary view in side elevation showing the fulcrum sectors, load controlled load 35 cam sectors and co-operating driving sectors.

Figure 5 is a plan of the parts shown in Fig. 4; and

Figure 6 is an enlarged fragmentary view, partly in section, on the line 6—6 of Fig. 2, showing the 40 means for attaching the indicator operating mechanism to the dial head housing.

Referring to the drawings 1 designates the indicator operating mechanism, constituting an important feature of the invention, which is mounted on spaced lugs 2 extending inwardly 45 from each side of the dial head housing 3, which is provided with a front dial glass frame and a rear cover plate (not shown). The indicator operating mechanism includes (Figs. 1, 2 and 3) 50 an integral assembly bracket 4 formed of bifurcated side sections 5 (Fig. 1), provided with transverse connecting webs 6 at their ends and having spaced upstanding arms 7 connected at their upper ends by cross arms 8, the spaced side sections 5 being adapted to engage the lugs 2 55

on the housing 3 and to be bolted thereto, while a brass washer 9 is inserted at one side in order to provide means for adjustment if necessary to overcome any inaccuracies in machining. Adjacent to the inner sides of the bracket arms 1 there are oppositely disposed groups of sectors, each group comprising two spaced outwardly extending fulcrum sectors 10 (Figs. 5 and 6) fixedly mounted on a common, floating shaft 11, each fulcrum sector 10 being suspended from a flexible steel tape 12 on which the fulcrum sector 10 is adapted to automatically turn and rock under influence of the load or out of level conditions, whereby in the latter instance the flexible tape 12 will unwind from one fulcrum sector 10 in proportion as the flexible tape 12 is taken up by the opposed fulcrum sector 10. Each flexible tape 12 is attached by clamping means 13 to the lower end of its respective fulcrum sector 10 and is secured at its upper end to the cross arm 8 of the bracket 4 (Fig. 2), whereby the co-operating fulcrum sector 10 and flexible tape 12 act as a fulcrum means as will hereinafter be described, while guide plates 14 (Fig. 3) secured to the bracket 4 serve to guide and retain the tapes 12 in position and thus prevent displacement of the fulcrum sectors 10 and co-operating mechanism.

Between the two spaced fulcrum sectors 10 there is mounted on the common shaft 11 on the side remote from their spaced center a load cam sector 15 (Figs. 5 and 6), which extends outwardly and is carried by an offset arm 15a adapted to centrally dispose the sector 15 with relation to the sectors 10 and is fixedly mounted on the common shaft 11 so as to minimize friction. The load cam sector 15 is provided with a flexible steel tape 16, secured by clamping means 13 to its upper end, while the lower end of the tape 16 is secured to a pivotally mounted vertical load member 17, attached to a horizontally disposed equalizer or cross bar 18 operatively connected to the weighing mechanism (Fig. 2). Interposed on the inner side of the spaced center of the fulcrum sectors 10 is an inwardly extending driving sector 19 (Figs. 4 and 5) carried by an offset arm 19a and fixedly mounted on the common shaft 11 so that in each group of sectors the load sector 15 and driving sector 19 are disposed in longitudinal alignment with each other, a flexible steel tape 20 is secured by clamping means 13 to the upper end of the driving sector, while the lower end of the tape 20 is secured by clamping means 13 at its lower end to a pendulum sector 21 (Fig. 2), which is pivotally mounted on a shaft 22 carried by ball bearings 23 and mounted in the spaced bracket sections 5.

Extending downwardly from each pendulum sector 21 is a pendulum rod 24 having a threaded portion 25, on which is slidably mounted an adjustable pendulum weight 26 (Fig. 2) provided with spaced lock nuts 27 engaging the threaded portion 25, for holding the pendulum weight 26 in the proper position. Each pendulum weight is provided with a set screw 28, seated in an opening 29 in the pendulum weight and adapted to engage a longitudinal groove 30 in the rod 24, whereby the pendulum weight 26 is prevented from turning. It will be noted that the various co-operating sectors and cam sectors are oppositely disposed in groups on each side of the bracket 4, the faces of the fulcrum sectors 10 and the load cam sectors 15 facing outwardly and the faces of the driving sectors 19 and pendulum sectors 21 inwardly.

Attached by clamping means 19a to the tapes 20 connecting the driving sectors 19 and the pendulum sectors 21, is a vertically disposed bifurcated rack driving bracket 31 (Figs. 1 and 2), preferably and having spaced arms 32 and 33, the upper arms 32 of which pass upwardly beyond the limit of travel of the driving sectors 19, while the lower arms 33 pass downwardly below the limit of travel of the pendulum sector 21. This particular driving member construction provides means for stiffening the tapes 20 and preventing the sector mechanism from getting out of position. Pivotally mounted on a pin 34 carried by driving bracket cross arms 35 and located therebetween is a depending toothed rack 36 adapted to mesh with a pinion 37 mounted on the pinion shaft 48, upon which is mounted a hub 39 carrying an indicator 40, cooperating with the dial 41, by which arrangement efficient and positive driving means is provided for driving the pinion 37 and the indicator 40. In order to provide proper contact between the teeth of the rack 36 and the teeth of the pinion 37 the pin 34 carrying the rack 36 is placed off center with relation to the axis of the pinion 37 (Fig. 2), while a roller 42 mounted on one of the H-shaped driving member side sections 5, is adapted to engage the back of the rack 36 and thereby hold the teeth of the rack and the pinion in engagement and prevent them from getting out of mesh, especially when shocks are sustained by the scale mechanism in moving it about or otherwise.

The fulcrum sectors 13 and driving sectors 19 are fixedly secured to the shaft 11 by pins 43 and the load cam sectors 15 are operatively connected to each respective group of sectors so that all the sectors in a group will move together under control of its co-operating load cam sector 15 (Figs. 4 and 5). In order to provide means for connecting the load cam sectors 15 to the particular group of sectors and thus transmit the load to the driving sectors 19, each load cam sector 15 is provided with an extension 44, which extends between two opposed adjustable screws 45 carried by bosses 46 integral with a side face of each driving sector 19, while lock nuts 47 serve to hold the screws 45 in their adjusted position. Further, the outer fulcrum sector 10 of each group of sectors is provided with an elongated boss 48 adjacent to its bearing portion, which has a transverse elongated slot 49 through which a locking screw 50 passes and is seated in a threaded opening 50a in a co-operating boss 51 on the load cam sector 15. By means of the adjustment of the screws 45 and then the locking of the locking screw 50 in the co-operating slot 49 proper adjustment is effected of the load cam sectors 15, in order to compensate for the unequal resistance offered by the pendulums 26 as they swing through their arc of movement, when the dial head mechanism is being sealed.

The vertical load members 17, which extend between the bracket side sections 5, are provided at their upper ends with upwardly extending guide arms 52 (Fig. 2), bolted thereto and adapted to provide a guide and track for each tape 16 on which its co-operating load cam sector 15 rocks, as well as to provide means to hold in position laterally the load cam sectors 15 and the other co-operating sectors and parts of the indicator driving mechanism, thereby preventing their displacement when the scale is being transported or moved about, as well as lateral displacement of the cross bar 18. At the lower end of the load members 17 is a downwardly extending

tongue portion 53 reduced in thickness and having a shoulder 53a, on which tongue portion there is pivotally mounted on a pin 54a carried by the extended tongue portion 53 an extension member 54 attached to a fixed depending rod 55, slightly spaced from the shoulder 53a of the load member 17, so as to permit limited lateral movement of each load member 17 and its guide extension 52 by their pivotal mounting on the extension member 54, thereby allowing free movement of the load cam sectors 15 without any friction or binding of the parts.

Secured in the lower end of each extension member 54 is the depending, threaded rod 55 which extends down through an end block 56 of the cross bar 18, which is formed of the end blocks 56 and spaced longitudinal bars 57 bolted to the end blocks. The rod 55 is provided with upper and lower lock nuts 58 engaging the upper and lower edges of the equalizer bar 18, thereby providing an adjustable connection on both sides of the equalizer bar. In order to provide means for preventing any undue lateral displacement of the various co-operating sectors and pendulum mechanism there are mounted in the base of the connecting webs 6 of the bracket 4 adjusting screws 59 adapted to be adjusted so as to just clear the end blocks 56 of the cross bar when the indicator is in the zero position on the dial. For the purpose of limiting the outward travel of the pendulum weights 26 opposed adjustable stops 60 are located on each side of the dial head housing 3 in the path of travel of the pendulum weights and comprise a plate 61 provided with elongated slots 62 and attached by bolts 63 to the side of a lug 3a integral with the dial head housing 3, whereby the plates 61 may be adjusted to the proper position and locked there by the bolts 63.

It is to be particularly noted that the disposition of the opposed groups of allied fulcrum sectors 10, load cam sectors 15 and driving sectors 19 in conjunction with the vertically operating driving member 31 is such that a powerful and effective driving force is delivered by the pull of the load upon the driving sector 19 and the driving member 31 and hence on to the rack 38 and pinion 37 carrying the indicator spindle 38. It is evident, therefore, that a powerful pull will be exerted by the driving member 31 on the pinion 37 and thereby greater power is provided to overcome friction in the rack and pinion and thus assist greatly in rendering the indicator more sensitive and accurate.

The means for transmitting the weight of the load includes a link 64 having at its upper end a yoke 65 carrying a pivot block 66, which is mounted on a knife edge pivot 67 transversely disposed between the spaced side bars 57 in the center of the equalizer bar 18. The lower end of the link 64 is hooked to an intermediate link 68, which in turn is hooked to a yoke pivotally connected to the beam and draft rod (not shown). By the linkage thus employed the pull exerted by the load is passed directly and forcibly without any deflection from the main lever (not shown) and draft rod (not shown) pivotally connected thereto, to the beam and hence to the load equalizer bar 18 of the dial head mechanism, thereby effecting a continuous, direct line pull upon the equalizer bar 18 and thus increasing considerably the power transmitted to the load cam sectors 15 to actuate the indicator pinion 37.

In operation when a load has been placed on the platform (not shown) the force exerted by

the load is transmitted in a direct line to the draft rod 68 which pulls down the load cross bar 18 and the load force is in turn applied to the tapes 16 connected to the load cam sectors 15 and hence to the fulcrum sectors 10 and driving sectors 19, and finally through the connecting tapes 20 the load force is applied very effectively to the pinion driving member 31 (Figs. 2 and 4). By this arrangement the fulcrum sectors 10 are caused to rotate and roll up on their respective depending tapes 12 attached to the housing 3, thereby causing the inner driving sectors 19 to move upwardly and pull their co-operating tapes 20, connected to the pinion driving member 31 carrying the rack 38 meshing with the indicator 15 shaft 38, in the same upward direction and thus rotate the indicator shaft and indicator 40.

Simultaneously the vertical tapes 20 connected to the driving sectors 19, driving member 31 and the pendulum sectors 21 are pulled upwardly causing the sectors to rotate about their axis and the load offsetting pendulum weights 26 to travel toward the center line of the dial head housing 3. The motion of these pendulum weights 26 offers a resistance to the load on the platform and they continue to move inwardly until the load on the platform is balanced and the dial head mechanism has come to rest. When the load has been removed from the scale the indicator 40 under influence of the pendulum weights 26 is returned to zero.

It is obvious that this dial head mechanism provides superior and efficient means for applying a powerful driving pull upon the indicator shaft.

While I have shown a preferred embodiment of my invention, it is evident that various modifications of the invention may be made that will come within the scope of the invention and I do not desire, therefore, to be limited to the exact details of construction shown and described.

I claim:

1. In a weighing scale, automatic weight indicating mechanism including oppositely disposed rockable sectors, load counterbalancing means comprising oppositely disposed pendulum sectors, flexible tapes connecting the said rockable and pendulum sectors and constraining the said sectors to move in unison, and an intermediate rack driving member disposed between the said flexible tapes and secured thereto.

2. In a weighing scale, automatic weight indicating mechanism including oppositely disposed rockable sectors, load counterbalancing means comprising oppositely disposed pendulum sectors spaced from and located below the said rockable sectors and in vertical alignment therewith, flexible tapes connecting the said rockable and pendulum sectors, and a transversely disposed rack driving member attached to the said flexible tapes midway between the rockable and pendulum sectors.

3. In an automatic scale, weight indicating mechanism including a pair of oppositely positioned rockable sectors, load counterbalancing means comprising a pair of oppositely positioned pendulums, depending flexible and aligned tapes connecting the said rockable and pendulum sectors, and an indicator operating device spanned between the said flexible tapes and intermediate of the rockable and pendulum sectors.

4. In an automatic scale, weight indicating mechanism including an indicator, a pair of oppositely positioned rockable sectors, a pair of oppositely positioned pendulum sectors located be-

low the rockable sectors and spaced therefrom, flexible and aligned tapes connecting the said rockable and pendulum sectors and constraining each rockable sector and its co-operating pendulum sector to move in unison, and a transverse indicator operating member located between and attached to the said flexible tapes for vertical movement thereby.

5. In an automatic scale, weight indicating mechanism including a pair of oppositely positioned rockable sectors having inwardly facing arcuate portions, a pair of oppositely positioned pendulum sectors located below the said rockable sectors and provided with inwardly facing arcuate portions, flexible and spaced tapes connecting the said rockable and pendulum sectors and attached to the said arcuate portions thereof and constraining each rockable sector and its co-operating pendulum sector to move in unison, and a vertical rack driving member mounted between the said flexible tapes and attached thereto midway between each co-operating pair of rockable and pendulum sectors.

6. A weighing scale comprising automatic weight indicating mechanism including oppositely disposed groups of sectors, each group being fixedly mounted on a common shaft and consisting of spaced fulcrum sectors fixedly mounted on the shaft, a load cam sector interposed between the fulcrum sectors, mounted on the said shaft and operatively connected to the weighing mechanism, a driving sector interposed between the load cam sector and one of the fulcrum sectors and fixedly mounted on the said shaft, adjustable locking means for operatively connecting the load cam sector to the co-operating fulcrum sector including a locking screw inserted in a transverse elongated co-operating opening in the fulcrum sector and engaging a threaded opening in the co-operating load cam sector, and extension means carried by the said load cam sector for transmitting the load from the weighing mechanism to the driving sector consisting of an extension member extending from the apex of the load cam sector, and adjustable connecting means carried by the said driving sector adapted to cooperate with the said extension member of the load cam sector inoperatively connecting the load cam sector to the driving sector, the said adjustable means including two opposed, adjusting screws mounted in bosses on the inner face of the driving sector, between which screws the said extension member of the load cam sector extends.

7. A weighing scale comprising weighing mechanism automatic weight indicating mechanism including oppositely disposed groups of sectors, each group consisting of spaced fulcrum sectors suspended from flexible tapes and rockable thereon, a driving sector operatively connected by a flexible tape to the said weight indicating mechanism and a load cam sector, a horizontally disposed cross bar operatively connected to the weighing mechanism, and vertically extending oppositely disposed load members connected by flexible tapes to the load cam sectors and pivotally mounted with limited lateral play, on the said cross bar, each member carrying a vertical guide member adapted to provide a lateral guide and track for each load cam sector, on which guide member its co-operating load cam sector rocks and adapted further to hold in position the load cam sector, thereby preventing lateral displacement of the load cam sector and the co-operating sectors.

8. A weighing scale comprising automatic weight indicating mechanism including oppositely

disposed groups of sectors, each group consisting of spaced fulcrum sectors suspended from flexible tapes and rockable thereon, a driving sector operatively connected by a flexible tape to the said weight indicating mechanism, a load cam sector operatively connected by a flexible tape to a cross bar connected to the weighing mechanism, and spaced guide plates pivotally mounted on the said cross bar and adapted to provide for limited lateral movement of the fulcrum sector tapes as well as to retain them in position and thereby prevent jamming or displacement of the said fulcrum sectors and the co-operating mechanism in operation.

9. A weighing scale comprising automatic weight indicating mechanism, actuating mechanism for the said weight indicating mechanism, the weight indicating mechanism including oppositely disposed groups of sectors, each group consisting of spaced fulcrum sectors suspended from flexible tapes and rockable thereon, a driving sector operatively connected to the mechanism actuating the said weight indicating mechanism, a cross bar connected to the weighing mechanism, a load cam sector operatively connected by a flexible tape to the said cross bar, and vertical, opposed load members mounted on the said cross bar and adapted to prevent lateral displacement of the various sectors and each vertical member comprising an upwardly extending guide arm secured thereto, a downwardly extending tongue portion having an extension member pivotally mounted thereon and slightly spaced from the end of the guide arm.

10. A weighing scale comprising automatic weight indicating mechanism, actuating mechanism for the said weight indicating mechanism, the weight indicating mechanism including oppositely disposed groups of sectors, each group consisting of spaced fulcrum sectors suspended from flexible tapes and rockable thereon, a driving sector operatively connected to the mechanism actuating the said weight indicating mechanism, a cross bar connected to the weighing mechanism, a load cam sector operatively connected by a flexible tape to the said cross bar, and vertical, opposed load members mounted on the said cross bar and adapted to prevent lateral displacement of the various sectors and each vertical member comprising an upwardly extending guide arm secured thereto, a downwardly extending tongue portion having an extension member pivotally mounted thereon and slightly spaced from the end of the guide arm, and a threaded rod secured in the lower end of the said extension member and an end block carried by the said cross bar and having upper and lower lock nuts mounted on the said rod adapted to engage the upper and lower edges of the end block and thereby permit adjustment vertically of the guide arm.

11. A weighing scale comprising weighing mechanism, a revolvable weight indicator, actuating mechanism for the said indicator, automatic weight indicating mechanism including oppositely disposed groups of sectors, each group being fixedly mounted on a separate transversely disposed shaft, and each group consisting of spaced, rockable fulcrum sectors, a driving sector and a load cam sector operatively connected to the weighing mechanism, the fulcrum sectors and load cam sectors of each group extending outwardly from the shaft, while the driving sector extends inwardly therefrom and is operatively connected by a flexible tape to the said

indicator actuating mechanism, oppositely disposed pendulum sectors, each pendulum sector being attached to the lower end of one of the said flexible tapes and in vertical alignment with the co-operating driving sector, the indicator actuating mechanism comprising a driving member attached to the said flexible tapes and interposed between the driving sectors and the pendulum sectors.

14. A weighing scale comprising weighing mechanism, a revolvable weight indicator, actuating mechanism for the said indicator, automatic weight indicating mechanism including oppositely disposed groups of sectors, each group being fixedly mounted on a separate transversely disposed shaft and consisting of spaced, rockable fulcrum sectors, a driving sector and a load cam sector operatively connected to the weighing mechanism, the fulcrum sectors and load cam sectors of each group extending outwardly from the shaft, while the driving sector extends inwardly therefrom and is operatively connected by a flexible tape to the said indicator actuating mechanism, oppositely disposed pendulum sectors, each pendulum sector being attached to the lower end of one of the said flexible tapes, the indicator actuating mechanism comprising a transversely disposed driving member having spaced arms attached midway of the said flexible tapes and adapted to be moved thereby under influence of the load.

15. A weighing scale comprising weighing mechanism, a revolvable weight indicator, actuating mechanism for the said indicator, automatic weight indicating mechanism including oppositely disposed groups of sectors, each group being fixedly mounted on a separate transversely disposed shaft and consisting of spaced, rockable fulcrum sectors, a driving sector and a load cam sector operatively connected to the said weight indicating mechanism and to the weighing mechanism, the weight indicating mechanism including oppositely disposed groups of sectors, each group being fixedly mounted on a separate transversely disposed shaft and consisting of spaced, rockable fulcrum sectors, a driving sector and a load cam sector operatively connected to the said equalizer bar, the fulcrum sectors and load cam sector extending outwardly, the driving sector extending inwardly and being operatively connected to the said indicator actuating mechanism, and oppositely disposed pendulum sectors, each pendulum sector being connected by a flexible tape to its co-operating driving sector in its group of sectors, the said indicator actuating mechanism including an intermediate transversely disposed driving member attached to and movable with the said flexible tapes, comprising upper and lower spaced arms and a cross arm carrying means for actuating the said indicator.

16. A weighing scale comprising weighing mechanism, a revolvable weight indicator actuating mechanism for the said indicator, automatic weight indicating mechanism, an equalizer bar operatively connected to the said weight indicating mechanism and to the weighing mechanism, the weight indicating mechanism including oppositely disposed groups of sectors, each group being fixedly mounted on a separate transversely disposed shaft and consisting of spaced, rockable fulcrum sectors, a driving sector and a load cam sector operatively connected to the said equalizer bar, the fulcrum sectors and load cam sector extending outwardly, the driving sector extending inwardly and being operatively connected to the said indicator actuating mechanism, and oppositely disposed pendulum sectors, each pendulum sector being connected by a flexible tape to its co-operating driving sector in its group of sectors, the said indicator actuating mechanism including an intermediate transversely disposed H shaped driving member attached to and movable with the said flexible tapes and comprising upper and lower spaced arms and a cross arm, a pinion carried by the said indicator and mounted below the cross arm, and a depending toothed rack pivotally mounted on a pin carried by the cross arm and adapted to mesh with the said pinion and thereby actuate the indicator under influence of the load.

ALFRED BOUSFIELD.
